UNITED STATES PATENT OFFICE.

WALTER S. WHITE, OF JAMESTOWN, NEW YORK.

FOOT-CLEANER.

SPECIFICATION forming part of Letters Patent No. 712,110, dated October 28, 1902.

Application filed April 19, 1902. Serial No. 103,828. (No model.)

To all whom it may concern:

Be it known that I, WALTER S. WHITE, residing at Jamestown, in the county of Chautauqua and State of New York, have invented 5 a new and useful Foot-Cleaner, of which the following, taken in connection with the accompanying drawings, is a full, clear, and exact description.

My invention relates to devices for cleaning 10 the boots and shoes before entering the house; and the object of my improvement is to make a combined scraper and brush which can be instantly reversed with the foot and which automatically locks itself firmly in position.

15 In the drawings, Figure 1 is a front elevation of my foot-cleaner with scraper in position for use. Fig. 2 is an elevation of the tripper end, showing the cleaner partly turned. Fig. 3 is an elevation of the other end and 20 with the brush held upright. Fig. 4 is a plan view of cleaner with scraper uppermost. Fig. 5 is a modification of tripper. Fig. 6 is a front elevation of a modification of my foot-cleaner without a tripper.

25 Similar numerals refer to corresponding parts.

10 is the frame, which is screwed down to the step or porch-floor and has uprights 11 and 11', with suitable openings therein to 30 hold the reversible cleaner. The reversible cleaner is made with a yoke 19, having brush 12 on one side and a scraper 13 on the other. The yoke has a round trunnion 14 at one end and a rectangular trunnion 15 at the 35 other end to work in the openings or bearings 16 and 17 in the uprights 11 of the frame. The round trunnion 14 has a suitable round hole 16 therefor in one of the uprights 11. Rectangular trunnion 15 has a round opening 40 17 therefor in the other upright 11', whose diameter is a little greater than trunnion 15, so that it can easily turn therein. At the lower side of opening 17 there is a rectangular opening 18 or notch, into which trunnion 45 15 fits and which holds or locks it and the yoke rigidly in position. End 15 of the yoke is easily raised out of the locking-slot 18, and the cleaner will then turn freely on the round trunnion 14. I cut one side 23 of notch 18 a 50 little lower than the other, so that when flat trunnion 15 turns over it will ride down on

lower side 23 and striking against the other side will fall into notch 18, thus insuring a single reversal and no more.

I usually cast the two trunnions in a yoke 55 of one metal piece 19 with the foot-scraper 13 thereon, the casting 19 covering the back corner of the brush-head 20, so that the scraper 13 is always at the farther side from the user, and the scrapings will fall away from the 60 cleaner and out of the way. The spring of the brush in like manner throws the dirt away from the cleaner and leaves it free to turn. The yoke 19 is so made as to hang brush 12 a little to one side, so that it will 65 overbalance and revolve when trunnion 15 is raised out of rectangular lock 18.

To trip or turn the yoke, trunnion 15 is extended out and a tripper 21 is attached thereto. I prefer an S-shaped tripper, as shown, since 70 it turns the yoke over and does not allow it to go farther. A circular tripper 22 might be used, but would be liable to turn the yoke too far.

In using the tripper to turn the yoke it is 75 caught with toe and raised, and at the same time the toe is drawn toward the person, thus giving it a quick turn as the tripper turns off the foot. This turning is aided by the brush-head being off its balance, and it will be seen 80 that there is no need of touching the yoke with the hand in order to reverse it.

Tripper 21 may be left off, as shown in Fig. 6, and the yoke and brush could be easily turned by inserting the toe under the 85 yoke near to upright 11' and raising the trunnion 15 out of lock 18. Then drawing the foot toward you the yoke is reversed on round trunnion 17 like a swivel. The one bearing turning easier than two and the yoke being 90 hung out of balance, as stated, the placing of the metal yoke to one side of the brush-head causes the yoke to roll off the toe, and trunnion 15 falls again into lock 18 as it reverses. The only objection to this form and 95 why I add tripper 21 is that brush 12 or scraper 13 are liable to be unclean and soil the shoe. This form would make a cheap and serviceable foot-cleaner.

I usually make the frame in one piece, with 100 suitable lugs and openings for screwing to the floor or step.

The scraper 13 is usually made with the rounded ends 24 24, which are convenient to clean out around the shoe-sole.

I claim as new—

- 5 1. A boot and shoe cleaner comprising a frame having suitable uprights and means for fastening the frame to a support, a yoke having a brush on one side and a foot-scraper on the other, a round trunnion at one end
10 of said yoke and a round bearing therefor in one of said uprights, and the other end of said yoke having a rectangular trunnion and a bearing therefor in the other of said uprights in which it can be both turned and
15 locked, substantially as and for the purpose specified.
2. A boot and shoe cleaner comprising a frame having suitable uprights and means for fastening the frame to a support, a yoke hung in said uprights having a scraper on one side and a brush on the other side, said yoke hung off its balance to aid in turning the same, and a suitable tripper for turning the said yoke.
- 25 3. In a boot and shoe cleaner a frame hav-

ing uprights and a metal yoke hung therein on round and square trunnions, a foot-scraper on one side of said yoke and a brush attached to the other side, a circular opening in said frame for revolving said rectangular trunnion and having a locking-notch to receive and hold the same, and a tripper for said yoke, substantially as and for the purpose specified.

4. A boot and shoe cleaner comprising a frame having suitable uprights and means for fastening the said frame to a support, a yoke having a round trunnion at one end and a square or rectangular trunnion at the other, a brush and suitable means for securing the same in said yoke, and an S-shaped tripper attached to said rectangular trunnion, substantially as and for the purpose specified.

In testimony whereof I have signed my name to this specification in the presence of 45 two subscribing witnesses.

WALTER S. WHITE.
